INVENTOR
Walter H. Smith.
BY
Mark G. Brown
ATTORNEY

UNITED STATES PATENT OFFICE.

WALTER H. SMITH, OF TULSA, OKLAHOMA.

SIGN.

Application filed August 21, 1926. Serial No. 130,669.

My invention relates to illuminated signs and more particularly to a lamp box for use in connection therewith, the principal object of the invention being to provide a box of that character which is simple and economical in construction, which may be easily and quickly assembled or disassembled, in which ready access may be had to contained light bulbs for renewals or repairs and which is slight in appearance.

In accomplishing this object I have provided improved details of structure, the preferred forms of which are illustrated in the accompanying drawings wherein:

Fig. 1 is a perspective view of an illuminated sign embodying my invention, illustrating a preferred method of hanging the sign.

Fig. 2 is an enlarged diametrical section of the sign.

Fig. 3 is a sectional view on the line 3—3 of Fig. 2.

Fig. 4 is an enlarged detail perspective view of portions of the lamp box, the lens and associated elements, parts being in section.

Referring more in detail to the drawings:

1 designates the sign here shown to be circular in contour and comprising an outer, annular rim portion, preferably composed of the side members 2 and 3 of sheet metal, each having an inturned rib 4 near its inner edge forming an outwardly facing V-groove 5, the inner edge of the sheet being straightened at the inner edge of the groove to form a flange 6 in alignment with the body of the sheet.

Located at intervals about the inner edge of the rim and extending between the rim sheets 2 and 3 adjacent the rib 4 are spacing lamp brackets 7, each having edge flanges 8 adapted to lie along the faces of the sheets 2—3 and secured thereto by bolts 9. The sheets 2—3 are spaced at their outer edges by a ring 10, also of sheet metal, having edge flanges 11 overlying the faces of the sheets 2—3 and secured thereto by screws 12, the sheets 2—3 and the ring 10 forming a rim about the lamp box, the inner edge of which is spaced by the brackets 7. The remainder of the box is formed of the ribs 4 on the inner ends of the sheets 2—3 and the lenses 11', the edges of which fit within the V-shaped grooves 5 with their inner surfaces

lying flat against the inner walls of the ribs 4, the lenses being held to their seats by keeper rings 13, preferably secured to the adjacent seats 2—3 by the same bolts 9 which anchor the brackets 7 thereto.

The inner edges of the keeper rings 13 are bevelled to lie flat against the outer surfaces of the lenses to form an extended contacting surface of the keeper ring against the lenses, thereby avoiding breakage of the lenses.

Attached to the outer faces of the brackets 7, to lie within the rim portion of the sign are lamp sockets 14 preferably multiple for carrying clusters of lamp bulbs 15, having wires 16 leading through the lamp box and the ring 10 to connection with a source of current.

The name of an establishment or other advertising matter (not shown) may be painted on the lenses to be visible during the day time and from the interior illumination at night.

The sign may be suspended from any suitable support, but preferably by links 17 from an ornamental pole 18, the links connecting with eyelets 19 on the rim of the sign.

It is apparent that a lamp box, the parts of which are constructed as described, may be easily and quickly assembled, that it is substantial, that the lenses may be easily and quickly placed on the box or removed therefrom for replacement of the lamp or for repairs, and that the box when assembled is of slight and attractive appearance.

What I claim and desire to secure by Letters-Patent is:—

A sign comprising a rim portion formed of spaced rings forming a lamp box and central openings and having outwardly facing grooves at their inner edges, brackets secured to and extending between the inner edges of said rings, a housing ring secured to the outer edges of said rings, closing the lamp box, concavo-convex lenses having their edges seated in said outwardly facing grooves, keeper plates attached to the rim rings and overlying the lenses, and lamp sockets mounted on said brackets and extending into said rim portion.

In testimony whereof I affix my signature.

WALTER H. SMITH.
